DISPLAY BOX

Raymond E. Fink, East Haven, Conn., assignor
to National Folding Box Company, New Haven,
Conn., a corporation of New Jersey

Application February 25, 1944, Serial No. 523,922

2 Claims. (Cl. 206—44)

1

This invention relates to display containers.

More particularly, the invention relates to collapsible containers of paperboard or like yieldable sheet material for housing articles of merchandise of the nature of wrist watches and/or wrist bands, bracelets, necklaces and like articles characterized generally as of loop formation, also for jewelry and like articles, etc.

A feature of the invention resides in the provision of a panel or extension connected to, and preferably integral with, a suitable closure panel of the container proper.

Desirably, a container embodying the instant invention is designed to be positioned to rest upon its normal open side, the closure panel in this instance serving as the base of the display assembly, the display panel extending from the outer edge of the closure panel. To effect display of the contained article, the body of the container is elevated by turning movement about its hinge with the closure panel, the display panel being rotated outwardly to afford display of the article of merchandise, the body of the container being thus held in elevated position. To insure effectual retention of the body of the container in suitable elevated position, it is desirable to dimension the closure panel to extend laterally of the body of the container whereby the closure panel is brought to rest when it is moved to its closing position relative to the body of the container and to dimension the display panel at its free edge but slightly less than the parallel dimension of the interior of the container, whereby the display panel makes a friction fit with the inner faces of the end panels of the container at the stages when the container is placed in display position, i. e. when resting upon its closure panel and when the container is in closed position, at which latter stage the friction between the display panel and the inner faces of the end panels of the container functions to suspend the article of merchandise above the bottom panel of the container.

For containers embodying the invention and designed for the display of looped articles, the display panel may be provided at its lateral edges with notches to receive the loop material. For containers for the display of jewelry, the display panel may be provided with a blanked-out tongue or sets of tongues or the like, for receiving thereon or therebetween the jewelry or like article to be displayed.

Further features and objects of the invention will be more fully understood from the follow-

2

ing detailed description and the accompanying drawing, in which

Fig. 1 is a perspective view of a preferred form of the invention, illustrating the container in display position. In this instance a wrist watch and its wrist band are shown on display thereon.

Fig. 2 is a perspective view of the embodiment shown in Fig. 1, illustrated in its closed position.

Fig. 3 is a plan of a preferred form of blank, showing one manner of constructing the container of integral material such as paperboard or like yieldable sheet material.

Fig. 4 is a detail transverse sectional view on line 4—4 of Fig. 2.

Fig. 5 is a detail longitudinal sectional view on line 5—5 of Fig. 2.

Referring to the drawing:

The container proper indicated generally 10 may be of any desired assembly of construction. Specifically as illustrated the container 10 has its end and front and rear panels and its remaining closed side formed of a single blank in which the concerned panels are hingedly related to one another and set-up into position by folding and overlapping, without requirement of gluing. If preferred the container may be secured in set-up status by gluing pursuant to any conventional procedure.

As illustrated in the preferred embodiment shown in the drawings, the container 10 is provided with a closure panel 11 hingedly connected to the free edge of a side panel of the container 10, proper, and preferably integral with the material of such panel.

Associated with such closure panel 11 and preferably integral with the material thereof, there is provided the display panel 12 serving to support, in suitable display position, an article of merchandise.

As specifically indicated in the drawing, a watch 13 is attached to a wrist band 14 and held in display position by the provision of the oppositely disposed notches 15, 15 formed at the opposite lateral edges of the display panel 12.

In lieu of such notches 15, 15, or equivalent, the material of the display panel 12 may be blanked to form one or more tongues 19, or other suitable means provided, for holding in display position one or more articles of jewelry or the like.

The blank designated generally 16, shown in Fig. 3, illustrates one manner of manufacturing embodiments of the invention from a single sheet of material, such as paper-board or like yieldable sheet material. The blank includes the clo-

sure panel 11 hinged by the score line 17 to the side panel 10a of the container 10, also the display panel 12 hingedly connected with the closure panel 11. The display panel 12 is illustrated as provided with a set of tongues 19, sa., blanked from the material thereof, for positioning therebetween suitable articles of merchandise, such as jewelry.

As above indicated, and as illustrated in the drawing, the display panel is dimensioned in the direction parallel to its line of hinge with the closure panel but slightly less than the parallel dimension of the interior of the container, whereby the display panel makes a friction fit with the inner faces of the end panels of the container at the stages of display of the article of merchandise, as is illustrated in Fig. 1, and when the closure panel is moved to its closing position, as is illustrated in Figs. 4 and 5, at which latter stage the friction between the display panel and the inner faces of the end panels of the container tends to suspend the display panel and therewith the article of merchandise supported thereby out of contact with the bottom panel of the container, in protection of the article of merchandise against possible shocks.

Preferably, the closure panel 11 has a dimension in the direction parallel to its hinged connection with the display panel 12 exceeding the parallel dimension of the interior of the container, thereby providing one or more extensions or flanges 11a, see Figs. 2 and 5 at one lateral edge or both lateral edges of the closure panel, whereby the free edges of the lateral sides of the container serve to limit the movement of the closure panel therat, thus precluding the entry of the closure panel within the interior of the container proper.

The remainder of the blank forms no essential part of the invention, in that the body of the container proper may be constituted as preferred pursuant to conventional procedure, including the glued types as well as frictionally set-up types.

The container is closed by rotating the display panel 12, with its thereon positioned article of merchandise to pass the free edges of the container, and assume a position, as desired, such as at an angle to the horizontal, as indicated in Fig. 4, or substantially horizontal, as indicated in Fig. 5.

Whereas I have described my invention by reference to specific forms thereof, it will be understood that many changes and modifications may be made within the purview of the appended claims.

I claim:

1. A container for the display of merchandise,

said container being formed wholly of integral, yieldable sheet material and comprising a container proper having an open side; a closure panel for such open side hingedly connected to an edge of a certain panel of the container proper, said closure panel having a dimension parallel to the direction of its stated hinge greater than the parallel dimension of the interior of the container proper whereby said closure panel extends laterally at its opposite lateral end portions beyond the end panels of the container; and a display panel hingedly connected to the outer edge of said closure panel parallel to the line of the stated hinge of said closure panel with the said certain panel of the container proper, said display panel being dimensioned in direction parallel to the direction of its line of hinging with said closure panel slightly less than the parallel dimension of the interior of the container proper to effect frictional engagement with the inner faces of the stated end panels of the container proper, whereby said display panel is frictionally held in display position at the stage when the container as an entirety rests upon its said closure panel and whereby said display panel is held in suspended position interiorly of the container proper when said closure panel is moved to its closed position in engagement with the free edges of the panels of the container proper.

30 2. A blank of integral yieldable sheet material for forming a container for the display of an article of merchandise, comprising a central rectangular panel; four rectangular panels respectively hingedly connected at the margins of said central rectangular panel, two of said four rectangular panels hinged laterally to said central rectangular panel, serving as end panels of the container when set up, the remaining two of said four rectangular panels serving as side panels of the container when set up; a panel hingedly connected to an edge of one of said side panels which edge is parallel to its line of hinging with said central panel and serving as a closure panel for the container when set up, said closure panel being dimensioned to extend at its opposite lateral edges beyond the line of its said hinging; and a panel serving as a display panel hingedly connected to said closure panel at its margin parallel to its line of hinging with said side panel, said display panel being dimensioned in the direction parallel to its line of hinging with said closure panel less than but within range of frictional fit with the inner faces of said end panels of the container when the container is in display position and in closed position.

RAYMOND E. FINK.
